CLAIM

The ornamental design for a handrail ladder, as shown and described.

DESCRIPTION

FIG. 1 is a front view of the handrail ladder, showing my new design;

FIG. 2 is a back view thereof;

FIG. 3 is a left side view thereof;

FIG. 4 is a right side view thereof;

FIG. 5 is an enlarged top view thereof;

FIG. 6 is an enlarged bottom view thereof;

FIG. 7 is a perspective view of the handrail ladder in an open position; and

FIG. 8 is a perspective view of the handrail ladder in a closed position; and,

FIG. 9 is a right-side perspective view of the handrail ladder in a closed position.

1 Claim, 9 Drawing Sheets
